INVENTOR

Augusta Adler,
BY
G. W. Bullard
ATTORNEY

UNITED STATES PATENT OFFICE.

AUGUSTA ADLER, OF TACOMA, WASHINGTON.

TOURIST'S STOOL.

SPECIFICATION forming part of Letters Patent No. 669,497, dated March 12, 1901.

Application filed July 19, 1900. Serial No. 24,211. (No model.)

To all whom it may concern:

Be it known that I, AUGUSTA ADLER, a citizen of the United States, residing at 409 C street, in the city of Tacoma, in the county 5 of Pierce and State of Washington, have invented certain new and useful Improvements in Tourists' Stools, of which the following is a specification.

My invention pertains to stools or seats used 10 by tourists and by persons at picnics, in camp, on excursions, and at places of outdoor amusements, where an improvised seat will afford rest and comfort to the individual.

The object of my invention is to provide 15 such a seat made light and strong and which can be reduced to a small compact package to be easily carried on the person and be set up wherever a seat is desired. I attain this object by means of the device illustrated in the 20 accompanying drawings, in which—

Figure 1 represents the frame of the stool set up, the cushioned packing-bag being omitted. Fig. 2 represents the stool as set up for a child, with the cushioned packing-bag 25 detached and above the seat. Fig. 3 represents the stool set up complete for the use of an adult. Fig. 4 is a view of the under side of the seat of the stool, showing its spider-frame construction. Fig. 5 is a top view of 30 the foot or tripod of the stool. Fig. 6 is a view of the two sections of the tubular standard which supports the seat on the tripod. Fig. 7 is a view of the seat-frame taken apart and packed together for transportation, and 35 Fig. 8 represents the cushioned packing-bag as it appears with the seat packed therein.

Similar numbers refer to similar parts in the several views.

My stool comprises a thin disk-shaped seat 40 1, made of suitable material, preferably round and perforated. The seat rests on a spider-like frame 2, having a multiple of arms 3. The seat is attached to the spider by means of screws, rivets, or other means 4. The 45 spider is made with a smooth hole at its center, into which is fitted a tubular standard made in two sections 5 and 6. The two sections of this tubular standard are fitted together with a neat telescope joint, as seen at 50 7. The lower end of the standard is fitted into a socket in the center of the tripod foot-

piece 8. A cushion 9, fitted to the seat, completes the stool as a comfortable and useful article.

The socket-joints being neatly fitted, the 55 several parts can be easily put together and taken apart. Figs. 1, 2, and 3 illustrate the several parts put together, forming the stool as set up for use. A low stool for the use of a child is obtained by taking out the upper 60 section 5 of the tubular standard and using only the lower section 6.

The seat-spider is made with rounded notches in the arms, as seen at 10, over which is fitted a spring 11. These notches and 65 springs are so made as to admit and clamp the two sections of the tubular standard. The stool is packed by taking the several pieces apart and slipping the two sections of the tubular standard under the springs and 70 into the notches of the spider and placing above them the tripod, as shown in Fig. 7. It is to be observed that a cylindrical extension 12 from the under side of the tripod fits into the socket of the spider 2, and thus forms a 75 stable compact union of the several parts thus put together in the "knockdown." They are then placed into the cushioned packing-bag 9. This bag, it will be observed, is provided with a draw-string 13, hemmed into the 80 bottom edge. After the seat-frame is packed into the bag the mouth is drawn together by means of this string and the seat is reduced to a round flattened cushioned package. The draw-string is then passed through a small 85 loop 14 on the opposite side of the bag and at the edge of the seat, all of which is illustrated in Fig. 8. The string may then be hung on the arm or to a hook or button on the clothing of the person and carried with 90 ease. The loop 14 being at the edge of the seat will cause the package to rest with flat and cushioned side against the person.

The frame of the stool is preferably to be made of aluminium, though other suitable 95 materials may be used in its construction.

I am not limited to the proportions and details shown in the drawings, but reserve the right to vary them as may be most practicable in the construction of my invention. 100

The packing-bag makes a comfortable cushion for the stool and gives it the appearance

of a neatly-upholstered piece of furniture suitable for a home as well as for tourists' use.

Having thus described my invention, what I claim as new, and desire to secure by Letters 5 Patent, is—

1. A tourist's stool comprising a spider-frame, having spring-controlled cavities to receive portions of a "knockdown" standard, a seat attached to said frame, a sectional 10 standard whose upper end supports the spider-frame; a base-piece supporting the standard, and a cushion packing-bag to cover and inclose said stool, substantially as described.
- 15 2. A tourist's stool comprising a sectional standard, a base to support said standard, a seat supported on said standard and having a part thereof formed with cavities to receive the standard and a part of the base, a spring 20 for holding the standard in place, and a packing-bag to fit over and secure the several

parts in a compact package, substantially as described.

3. A tourist's stool comprising the spider-frame formed with a central socket to receive the end of a standard when upright and with a cavity to receive the standard in a "knockdown" position, means for holding the standard in said cavity, a base to support the standard and formed with an extension to fit in the 30 socket of the spider-frame in the "knockdown" condition of the stool, a seat portion to the frame, and means for securing the several parts together in their "knockdown" condition, substantially as described. 35

In testimony whereof I affix my signature in the presence of two witnesses.

AUGUSTA ADLER.

Witnesses:
